[57] CLAIM

The ornamental design for a battery for a computer, as
shown and described.

DESCRIPTION

FIG. 1 is a front elevational view of a battery for a computer,
showing my new design;

FIG. 2 is a rear elevational view thereof;

FIG. 3 is a top plan view thereof;

FIG. 4 is a bottom plan view thereof;

FIG. 5 is a right side elevational view thereof, the left side
being symmetrical with that shown;FIG. 6 is a front, top and right side perspective view thereof;
and,FIG. 7 is a right side elevational view thereof, showing the
state in use.The broken lines shown in FIG. 7 are for illustrative
purposes only and form no part of the claimed invention.
